C. I. Stephens INVENTOR
Niceto J. Evans

ATTORNEY

UNITED STATES PATENT OFFICE.

CHARLES T. STEPHENS, OF CHICAGO HEIGHTS, ILLINOIS.

KEY LOCK.

Application filed May 12, 1924. Serial No. 712,743.

To all whom it may concern:

Be it known that I, CHARLES T. STEPHENS, a citizen of the United States, residing at Chicago Heights, in the county of Cook and State of Illinois, have invented new and useful Improvements in Key Locks, of which the following is a specification.

This invention relates to new and useful improvements in piano key locks and more particularly to a device of this character which is particularly adapted for use upon a player piano whereby to lock the keys against movement when so desired. The main object of the present invention is the provision of an extremely simple and inexpensive device which may be quickly and readily applied to any well known make of player piano and adjusted for use in locking the keys of the key board against movement when so desired, during the playing of the instrument.

Another object of the present invention is the provision of a device for locking the keys of a key board in a player piano which can be quickly and readily installed, and the operating mechanism thereof is entirely out of sight, the only visible portion of the mechanism being the foot operated treadle which actuates the device for locking or unlocking the keys of the key board.

With the above and other objects in view the invention consists in the novel features in construction, the combination and arrangement of parts hereinafter more fully set forth, pointed out in the claims and shown in the accompanying drawings in which:—

Fig. 1 is a top plan view of a piano key board illustrating the application of my improved lock.

Fig. 2 is a longitudinal sectional view taken on the line 2—2 of Fig. 1.

Fig. 3 is a transverse sectional view taken on the line 3—3 of Fig. 2.

Fig. 4 is an elevation as indicated at 4—4 of Fig. 3.

Fig. 5 is a transverse sectional view taken on the line 5—5 of Fig. 3.

Referring more particularly to the drawings the numeral 1 indicates the key board of an ordinary player piano, the keys of the board being supported for pivotal movement upon the center support 2. Arranged above the key board and extending transversely of the keys at a point adjacent the inner ends thereof is a locking bar 3, the ends

of which are provided with suitable openings to receive the guide bolts 4 which are carried by the supporting shelf 5 of the key board and mounted upon these bolts are suitable coil springs 6, the tension of which normally moves the locking bar 3 upwardly against the nuts 7 threaded upon the upper ends of said bolts, thus when the locking bar is released the springs 6 will have a tendency to force the bar 3 upwardly and release the keys of the key board.

A connecting link 8 is attached to the central portion of the locking bar 3 and the lower end thereof is detachably connected to the central portion of a longitudinal shaft 9, the ends of which are mounted within suitable guides 10 to permit lateral movement of the shaft. The shaft 9 is connected to the upper end of a rod 11 by suitable loose connection 12 and the lower end of this rod is provided with a sleeve 13 adapted to embrace the crank arm 14 of the operating shaft 15. The operating shaft 15 is extended transversely of the key locking bar 3 and shaft 9 and is mounted for rotation in suitable bearings 16, the crank 14 being disposed between these bearings and attached to the outer end of the shaft 15 is a foot treadle 17 which is extended equally upon opposite sides of the shaft.

As noted in Fig. 3 the outer end of the shaft projects beyond the forward wall of the piano casing 18 and the foot treadle 17 is positioned upon the outer end of the shaft 90 as shown in this figure.

As shown in Fig. 3 the locking bar 3 has been moved downwardly against the upper surfaces of the key members of the key board to retain them in a locked position and the relative position of the crank 14 is clearly illustrated in Fig. 2 with the right portion of the crank disposed slightly beyond the gravity center of the same so as to securely retain the bar 3 against the tension of the spring 6 so that when the crank is released to its unlocked position the tension of the spring will readily raise the bar to release the keys.

In order to limit the swinging movement of the crank member 14 a stop arm 19 is attached to the shaft 15 at a point adjacent the crank, said arm having its outer end slightly turned as at 20 to form an engaging portion adapted to rest upon a stop 21 fixed to the bottom of the piano casing so as to prevent the outer end of the arm from

striking the bottom of the casing and creating unnecessary noise as well as injury to the casing.

In order to provide for the limited movement of the stop arm 19 in the opposite direction, a lug 22 is attached to the sleeve of the stop arm and this lug is adapted to abut against a stop button 23 supported upon the bracket 24 and disposed directly 10 in line with the path of movement of the arm 19 thus when the lug 22 is brought into direct contact with the stop member 23 the bar 3 will be arranged in a locked position.

From the above description taken in connection with the accompanying drawings it will be readily apparent that I have provided a simple and inexpensive device for locking the keys of a player piano key board in inoperative position during the playing 20 of the instrument through its own mechanism.

While I have shown and described the preferred form of my invention I wish it to be understood that various changes and 25 alterations may be carried out during the manufacture of the same without departing from the spirit of the invention or the scope of the appended claims.

Having thus described my invention what 30 I claim is:—

1. A device of the character described

including a locking bar extending transversely of the key board of a piano, an operating shaft extending transversely of the key board of a piano; an operating shaft 35 extending transversely of the bar, a crank on said operating shaft, a foot treadle upon one end of the shaft, means connecting said crank with the intermediate portion of said bar whereby rotation of the shaft will lower 40 the bar, means for raising said bar upon release of said shaft and means for limiting the rotation of the shaft in either direction.

2. A device of the character described 45 including a locking bar normally disposed transversely of the keys of the key board of a piano, coil springs disposed beneath the ends of said bar to retain the same in a normally arranged position, an operating shaft, a crank on the shaft, a vertically movable 50 shaft disposed longitudinally of the locking bar beneath the same, means forming connection between the longitudinal shaft and the intermediate portion of the shaft, additional means forming connection between the movable shaft and the crank, a foot treadle carried by the crank shaft whereby 55 to impart movement to the same, and means carried by the crank shaft for limiting the rotary movement of the same.

In testimony whereof I affix my signature.

CHARLES T. STEPHENS.
